US00D632285S

(12) **United States Design Patent**
Takahashi

(10) **Patent No.:** US D632,285 S
(45) **Date of Patent:** ** Feb. 8, 2011

(54) **ANTENNA**

(75) Inventor: **Yoshihide Takahashi**, Minato-ku (JP)

(73) Assignee: **NEC Corporation**, Tokyo (JP)

(**) Term: **14 Years**

(21) Appl. No.: **29/350,849**

(22) Filed: **Nov. 24, 2009**

(30) **Foreign Application Priority Data**

May 28, 2009 (JP) 2009-012018

(51) **LOC (9) Cl.** **14-03**

(52) **U.S. Cl.** **D14/230**

(58) **Field of Classification Search** ..... D14/138, D14/230-238, 299, 358, 240; D12/42, 43; 343/700 MS, 700 R-705, 711-713, 741, 343/748, 767, 795, 819, 840, 846, 866, 871-908; 455/90.2, 90.3, 91, 128, 269, 344, 347, 562.1

See application file for complete search history.
